MULTIPOLE SWITCH

Elwood T. Platz and Lawrence E. Fisher, Detroit,
Mich., assignors to Bulldog Electric Products
Company, Detroit, Mich., a corporation of West
Virginia

Application October 9, 1944, Serial No. 557,883

4 Claims. (Cl. 200—116)

1

This application relates to multipolar circuit controllers.

Two different multipolar circuit controllers are disclosed herein and these will now be described upon reference to the appended drawings. In these drawings,

Fig. 1 is a top plan view of one multipolar circuit controller wherein two single pole circuit controller units are arranged side by side; the interior parts are not shown, but the casings and exterior parts of the units are shown;

Fig. 2 is a back view as if in the direction of the arrow 2 of Fig. 1, showing the parts in the "on" or "closed" circuit position;

Fig. 3 is an end view as if in the direction of the arrow 3 of Fig. 1;

Fig. 4 is a view like Fig. 2, but showing the parts in the "off" or "open" circuit position;

Figs. 5 and 6 are illustrative views, with the casings removed, showing the parts in the "on" and "off" positions respectively;

Figs. 7 and 8 are additional illustrative views, with the casings removed, showing the parts in the "on" and "off" positions respectively;

Fig. 9 shows a tie-bar per se;

Fig. 10 is a top plan view of a second multipolar circuit controller, wherein two single pole circuit controller units are arranged back to back; the interior parts are not shown, but the casings and exterior parts of the units are shown;

Fig. 11 is a view as if in the direction of the arrow 11 of Fig. 10;

Fig. 12 is a view as if in section on line 12—12 of Fig. 10, but showing the parts in the "on" or "closed" circuit position; and

Fig. 13 is a view like Fig. 12, but showing the parts in the "off" or "open" circuit position.

Fig. 14 shows a single pole unit, an outside view;

Fig. 15 is an interior view, in "off" position;

Fig. 16 is an elevation view, in section on line 16—16, Fig. 15, in "off" position;

Fig. 17 shows a casing, per se;

Fig. 18 shows a handle, per se;

Fig. 19 is an elevation view in section, on line 19—19, Fig. 15;

Fig. 20 is a view like Fig. 16, in "on" position;

Fig. 21 is a transverse section view on line 21—21, Fig. 15.

In each of the two embodiments shown herein there are a plurality of single pole circuit controller units 9 combined for multipolar operation. In the embodiment of Figs. 1 to 9, the units happen to be side by side, as illustrated best in Fig. 1, whereas in the embodiment of Figs. 10 to 15

2

to 13, they are arranged back to back, as illustrated in Fig. 10.

The single pole controller units of the two embodiments are identical and the two embodiments differ merely in that the units are side by side in one case and back to back in the other, and in the construction and arrangement of the parts which interconnect the units to provide multipolar operation.

We will first describe a single pole controller unit per se with particular reference to the drawing and particularly Figs. 14—21. Each unit is practically the same as the switch shown in a prior patent, No. 2,385,727 of September 25, 1945, differing only in that to the switch of the patent there are added an operating part or pin 102 and an opening 103, both of which will later be described more in detail.

Each unit comprises a cup-shaped casing 10 whose open back is closed by a plate 11. Through the casing project line and load terminals 14 and 15. In the top of the casing 10 slides an exposed handle or actuator 17, biased outwardly by spring 31, and having cams, 62 and 71.

Within the casing, and secured to the line contact 14 is a stationary contact 44 adapted to be engaged by a contact 48 on the end of a movable contactor 49 to the body part of which is secured, by a pivot pin 51 formed as a rivet, a holding means in the form of a bimetal strip 52 forming a relatively movable part of the contactor. Pin 51 pivotally connects the contactor to a holding plate 53 of insulation. An operating spring 56 engages a lug 58 of the contactor to bias the hook end 60 of the bimetal strip against a holding means for the contactor, namely edge 61 of the holding plate, for latching, and also to bias the contactor to the open circuit or "off" position when the hook end of the bimetal strip

moves from the holding means, the edge portion of the holding plate, as by warping of the strip on overload, or as by being moved manually away from the holding means by movement of the handle downwardly. The operating spring also closes the circuit by moving the contactor upwardly, after the contactor is manually moved clockwise by handle 17 so that its hook end once more engages the holding means.

A cam 62 on handle 17 may move hook end 60 away from the holding means 61, the contactor then being rocked in a plane normal to the cover 11, and thereafter being swung by spring 56 on pivot 51, for circuit opening, moving at that time in a plane parallel to cover 11.

Another cam 71 on handle 17 may move plate

53 and contactor 49 downwardly to swing the contactor which rocks clockwise back to the position wherein its hook end 60 is once more held by the holding edge 61 of plate 53, after which, i. e., as soon as handle 17 is released, spring 56 can move both the plate 53 and contactor 49 to circuit closing position.

A flexible connector 65 connects the bimetal strip 52 to the load terminal 15 to complete the circuit.

As previously stated, the contactor 49 of each unit is provided with a pin 102 arranged to extend through a cutout or opening 103 in the back or cover 11 of the unit. Parts 102 and 103 are the only parts of the units hereof not found in the unit of Patent No. 2,385,727.

In the embodiment of Figs. 1 to 9 inclusive, the two units 10 are shown as mounted side by side on a mounting plate 101. This plate has several holes or openings 103a aligned with, though larger than the openings 103 of covers 11 and pins 102 project not only through openings 103 of the covers 11 but also through the openings 103a of the mounting plate 101.

When two units are side by side, they will have their two pins 102 projecting through the openings 103a of the plate 101 and will seat themselves in slots 104 of a tie-bar 105, extending across the covers 11 of the two units. The tie bar is guided by an appropriate guide 106 and its movement is limited by appropriate stops 106a. Thus, movement of one contactor will move the tie-bar 105 to cause a corresponding movement of the other contactor, effected in the following manner. Each contactor is mounted, not only to pivot on the axis of the pin 51, i. e., swing in a plane parallel to cover 11, but also to rock toward or away from cover 11 in a manner to release the end 60 of the bimetal strip 52 from the holding edge 61 of the holding plate 53. Thus, when the hook end 60 of one contactor is moved from its holding means 61, and subsequently begins to move, under the influence of its spring 56, the free end of its pin 102 will move downwardly and this will lower the tie-bar, whereupon the free end of pin 102 of the adjacent contactor will also be lowered, so as to cause the contactor of that unit to rock in a manner to free its hook end 60 from the holding edge 61 of its holding plate 53. Thereupon the spring 56 of the second unit will move its now released contactor rapidly to "open" circuit or "off" position.

For manual actuation of the two handles 17 in common, there is provided a common manual actuation. Thus hinged at 107 to mounting plate 101 is a handle 108, having a plurality of roller cams 109, each arranged to engage a handle 17 of a unit whereby all the unit handles 17 may be moved down simultaneously by moving down the handle 108 for causing or initiating simultaneous open or closing movement of the contactors of the various units.

It is noted that the tie-bar connects the contactors so that the movement of one from its holding means 61 causes similar movement of the other.

When the units are mounted back to back, as indicated in Figs. 10 to 13, the tie-bar is arranged to slide between the two units. This tie-bar, referenced 120, is mounted to slide in a T-shaped opening 121 of a plate 122, disposed between the backs of the units. The lower or enlarged portion of the opening 121 is in the form of a clear hole through which the pins 102 of the two units project, but from opposite directions. These pins 75

seat themselves in notches 123 of the enlarged portion or head 124 of the tie-bar 120. When either of the pins 102 moves vertically, as on movement of its contactor to or from its holding means, it will cause a corresponding movement of the tie-bar 120 and a corresponding movement of the pin 102 of the other unit for the same purposes that have previously been described with reference to the embodiment shown in Figs. 1 to 9.

10 The handles 17 of the two switches of Figs. 10 to 13 are connected by a bridging member 126, fastened by screws 127 to these two handles 17, for common manual actuation.

Now having described the circuit breakers herein disclosed, reference should be had to the claims which follow.

We claim:

1. In a multipole automatic circuit controller arranged for opening on all poles when any one opens, several switch contactors, several operating springs, one for each contactor, several holding means, one for each contactor, and a tie-bar directly connecting the contactors, arranged so that movement of one contactor from its holding means automatically moves the other contactors likewise from their holding means, directly through the tie-bar.

2. A multipole circuit controller comprising a plurality of complete and self contained, casing enclosed, assembled single pole circuit controller units, each having its own contactor, its own operating spring, its own and independent contactor holding means, and its own and independent automatic means for moving its contactor from its holding means, the multipole circuit controller having a means outside of the several single pole circuit controller units for mechanically and directly interconnecting the several contactors of the several units, constructed so that automatic movement of any one contactor from its holding means, in response to a circuit abnormality in the pole controlled by it, will cause a similar movement of the remaining contactors from their holding means by mechanical transmission of that movement of the first contactor to the remaining contactors, each contactor, as it moves from its holding means, being then moved to "open" circuit position by its own operating spring.

3. In a multipole automatic circuit controller arranged for opening on all poles when any one opens, several switch contactors, several operating springs, one for each contactor, several holding means, one for each contactor, and a tie-bar directly connecting the contactors, arranged so that movement of one contactor from its holding means automatically moves the other contactors likewise from their holding means, directly through the tie-bar, the controller also having several manual operators, one for each contactor, and a common actuator for moving the several manual operators, simultaneously, each manual operator having a means for moving its contactor from its holding means.

4. A multipole circuit controller comprising a plurality of complete and self contained, casing enclosed, assembled single pole circuit controller units, each having its own contactor, its own operating spring, its own and independent contactor holding means, and its own and independent automatic means for moving its contactor from its holding means, the multipole circuit controller having a means outside of the several single pole circuit controller units for mechanically and directly interconnecting the several contactors of

the several units, constructed so that automatic movement of any one contactor from its holding means, in response to a circuit abnormality in the the pole controlled by it, will cause a similar movement of the remaining contactors from their holding means by mechanical transmission of that movement of the first contactor to the remaining contactors, each contactor, as it moves from its holding means, being then moved to "open" circuit position by its own operating spring, the controller also having several manual operators, one for each contactor, and a common actuator for moving the several manual operators, simultaneously, each manual operator having a means for moving its contactor from its holding means.
